UNITED STATES PATENT OFFICE.

JOSEPH A. SILVER, OF NEW YORK, N. Y.

RAILROAD-TIE.

1,281,086.

Specification of Letters Patent.

Patented Oct. 8, 1918.

Application filed July 20, 1917. Serial No. 181,882.

To all whom it may concern:

Be it known that I, JOSEPH A. SILVER, a citizen of the United States, residing at New York, in the county of New York and State 5 of New York, have invented certain new and useful Improvements in Railroad-Ties, and I hereby declare that the following is a full, clear, and exact description thereof, reference being had to the accompanying 10 drawings, which form part of this specification.

The invention is a novel improvement in combined metal and concrete railroad ties or sleepers; and has particular reference to the 15 class of such ties using what are commonly termed "pot-sleepers."

The objects of the invention are: to provide a novel pot-sleeper consisting of an approximately oblong or elliptical hollow metallic body of peculiar construction filled 20 with concrete; to provide novel means for connecting opposite pot-sleepers to form a tie; to so construct the pot-sleepers that the rails can be readily attached thereto; to prevent creeping of the sleepers; to enable bolts 25 and rivets to be dispensed with in the connections between the pot-sleepers; and to simplify the construction, reduce the cost of manufacture, and facilitate the assembly 30 of parts of such ties.

I will explain the improvement in connection with the accompanying drawings which illustrate a practical embodiment of the invention; and summarize in the claims 35 the novel features and combinations of parts for which protection is desired.

In said drawings:

Figure 1 is a plan view of a section of track showing the general arrangement and 40 construction of the ties.

Fig. 2 is a side view of one of the pot-sleepers and connected tie-bar.

Fig. 3 is an enlarged detail transverse section on the line 3—3 Fig. 1.

Fig. 4 is an enlarged detail horizontal section on the line 4—4 Fig. 2.

Fig. 5 is a detail vertical section on the line 5—5 Fig. 4.

The tie comprises two similar opposite 50 pot-sleepers 1 connected by a tie-bar.

Each pot-sleeper consists primarily of an inverted hollow metal member whose greatest diameter lies parallel with the rail. Each of these members may be cast, but is

preferably stamped from sheet steel, in an 55 elliptical cup-shape; and the side walls 1^a thereof incline downwardly and outwardly from the top thereof as shown. At each end the member is provided with an extension or lip 1^b which depends below the lower edge 60 of the wall 1^a, is preferably curved and serves to prevent the pot-sleeper moving sidewise as well as lengthwise of the track. The side walls 1^a of the pot-sleeper are preferably internally flanged at their lower 65 edges, as at 1^d, for the purpose of stiffening the member and also to anchor and retain the concrete filling therein. The pot-sleeper is also preferably formed with a central opening 1^e which is surrounded by a depending internal flange 1^f, the lower edge of which flange is preferably turned inwardly as at 1^g.

For good practical purposes the pot-sleeper would be approximately five inches 75 in depth and its entire interior should be filled with concrete, indicated at 2; which concrete may be reinforced if desired in any suitable manner as by means of a metal screen 3, so that the concrete and metal member 80 become practically inseparably connected and together form the complete pot-sleeper. In some cases the pot-sleeper can be filled with asphalt so as to make it more elastic; this is desirable when used in stone 85 tunnels or on stone or metal foundations.

By having the sides of the sleeper 1 inclined or tapered as shown, it results that when the pot-sleeper is in use the concrete filling will always be pressed tightly against 90 the sides of the metal casing or member, and the concrete is thus prevented from loosening and the metal is prevented from vibrating, sounding or ringing, which is objectionable.

It will be seen that the complete pot-sleeper comprises a compound metal and concrete or asphalt structure, the concrete being practically incased within the metal member and not merely reinforced by it.

Each pot-sleeper is provided at each side of the opening 1^e and in line with the rail at opposite sides of the center line of the member with a series of key slots 1^h with any one of which the head 3^a of a fastening bolt 3^e may be engaged; these bolts are used to secure the clamps 3^c that engage the flanges of the rails and fish plates, the

clamps being secured on the bolts by nuts 3^e is indicated in Figs. 1-3.

At the inner side of each pot-sleeper is a member or casting 4 which is rigidly attached to or formed on the pot-sleeper and is provided with a socket or recess in its outer side, and the vertical side walls of said socket are oppositely inclined, as indicated at 4^a in Fig. 4. The upper and lower walls 10 of this member may be recessed at the mouth of the socket as indicated at 4^b in Figs. 1 and 3.

Detachably engaged with the member 4 are clamps 5 each of which is provided with 15 a tapered surface 5^a adapted to engage one of the opposed tapered surfaces 4^a of the member 4. The clamps 5 and the member 4 are preferably oppositely tapered as shown in Fig. 4 so that the more tightly the bolts 20 7 are drawn the more securely will the tie-bar be clamped.

The clamps 5 are provided with recesses 5^c in their opposed faces to engage a head 6^c on the end of a tie-bar 6; hereinafter 25 referred to. These clamps 5 are also provided with base-flanges 5^e which are notched as at 5^f (see Fig. 4) to engage between them the shank of a bolt 7, which has a head 7^e adapted to engage the flanges 5^e of the opposed clamp members 5.

The tie-bar 6 is preferably T-shaped in cross section and has an enlarged head 6^c on each end which head is adapted to be engaged by and between the clamp members 35 5 attached to each pot-sleeper and be rigidly secured to the pot-sleeper when the clamp members 5 are drawn into the recesses 4^b by tightening the bolt 7.

The bolt 7 extends through apertures in 40 the side wall of the pot-sleeper 1 and the adjacent inner wall 1^f into the opening 1^e, and may be secured by any suitable means. As shown it is confined by means of a wedge 8 engaging a slot 7^a in the bolt 7, and said 45 wedge is secured by a retainer 8^a engaged with any one of a series of perforations 8^a in the wedge, or the end of the wedge can be bent if desired to keep it in place after it is driven home. The bolt 7 is of such 50 length that when the wedge is driven home it will tend to draw the clamp members 5 into the tapered openings in the casting 4.

Owing to the taper of the clamps 5 and the member 4 the tighter the bolt 7 is drawn 55 the more securely are the clamps engaged with the tie-bar and with the member 4 and in this manner a rigid and durable connection is made between adjacent pot-sleepers without the use of bolts.

60 The heads 6^c of the tie-bar 6 engage within the notches 4^b of the members 4 and when the parts are properly positioned the sleepers cannot tilt or oscillate relative to each other.

65 The clamps 5 may be provided with re-

cesses 5^b in the edges of their jaws and the ends of the tie-bar may be provided with enlargements 6^a that engage recesses 5^b (see Fig. 4) and prevent the tie-bar becoming vertically displaced in the clamps. 70

The members 4 may be changeable, and when it is desired to slightly change the distance between rails to compensate for wear, or adjust the distance between opposite rails the tie bar and clamps can be removed, and one or both members 4 detached and replaced by other members thicker or thinner as required; then the tie bar and clamps can be replaced and fastened as before. This does not require changing the 80 tie bars, nor removing the devices that fasten the rails to the pot-sleepers. A clearance should be left between the inner ends of the clamps and the bases of the sockets in members 4, as indicated in Fig. 4, so that 85 the parts can be properly securely tightened when adjusted.

When the ties are used on electric railways, or where the track rails are used as conductors for electric signals insulating 90 fiber washers 9 can be placed between the heads 6^c of the tie-bar and the clamp members 5. A washer or washers 7^c can be placed on bolt 7 between the wall 1^f and the wedge 8 to enable the taper wedge 8 to 95 quickly tighten the bolt 7 to hold the clamps securely in place. A reinforcing member 7^d may be also interposed between the outer end of sleeve 7^s and the wall 1^a as indicated in Figs. 3 and 4. 100

This construction does away with nuts, bolts, and most of the parts can be readily stamped out of steel at low cost.

To prevent strain on the bolt 7 possibly drawing the walls 1^a and 1^f toward each other and crushing the concrete interposed between said walls, a sleeve 7^s is placed around the bolt 7 between the walls 1^a and 1^f, see Figs. 3 and 4. 105

My oval shaped pot sleepers, arranged as shown, will permit the desired longitudinal resiliency of the track without displacement thereof. By arranging the sleepers with their longest diameters lengthwise of the track rails the latter are more thoroughly supported, and the number of sleepers and tie bars required per mile of track is reduced without impairing the durability or firmness of the track structure. It is well known that road beds sink or pack directly 115 under the rails while the central portion of the bed remains comparatively high and unyielding; and this causes tracks built with ordinary transverse sleepers to teeter when trains pass thereover; but such teetering 120 cannot occur in a track built with my sleepers. 125

What I claim is:

1. A railroad tie comprising opposite pot sleepers each provided with a socket, clamps 130

- adapted to engage said socket, a tie-rod adapted to be engaged by said clamps, and means for fastening the clamps to the socket. 70
2. A railroad tie comprising opposite pot-sleepers each member having a tapered socket, clamps adapted to engage said sockets and means for fastening the clamps to the sockets. 75
3. In combination a pot-sleeper having a socket on its side, and a tie-bar provided with a head and clamps adapted to engage the head of the tie-bar and the socket member. 80
4. In combination a pot-sleeper, a tapered socket member on the side of the pot-sleeper, a tie-bar provided with a head and clamps adapted to engage the head of the tie-bar and the socket member. 85
5. In a railroad tie, a pot-sleeper having a member provided with a socket having tapered walls; and clamps adapted to engage the head of the tie-bar, and having tapered sides adapted to co-act with the tapered wall of the socket. 90
6. A railroad tie comprising opposite pot-sleepers each provided with a socket; clamps adapted to engage said sockets, a tie-rod adapted to be engaged by said clamps, bolts engaging said clamps and sleepers to secure the clamps to the sockets and means for fastening the bolts. 95
7. A railroad tie comprising opposite pot-sleepers each provided with a member having a tapered socket; clamps adapted to engage said sockets, a tie-rod adapted to be engaged by said clamps, bolts engaging said clamps and sleeper to secure the clamps to the members and means for fastening the bolts. 100
8. In a railroad tie, the combination of opposite pot-sleepers each having outwardly sloping walls and provided at each end with a depending lip adapted to anchor the sleeper; with a tie-rod, and clamps engaging said tie-rod to fasten the same to said sleepers. 105
9. In combination a pot-sleeper having a member provided with a socket; a tie-bar having enlargements adjacent its end, clamps adapted to enter the socket and engage the end of the tie-bar and provided with recesses to engage the enlargements upon the sides of the tie-bar. 110
10. In combination a pot-sleeper, a member at the side of the pot-sleeper provided with a socket having tapered walls, a tie-bar having enlargements adjacent its end; clamps provided with tapered sides adapted to enter the socket and to engage the end of the tie-bar, and further provided with recesses to engage with the enlargements upon the sides of the tie-bar. 115
11. In combination a pot-sleeper; a member on the side of the pot-sleeper provided with a socket; clamps adapted to engage the head of the tie-bar, and further provided with recesses to engage with the enlargements upon the sides of the tie-bar. 120
12. In combination a pot-sleeper; a member on the side of the pot-sleeper provided with a socket having tapered walls, clamps provided with tapered sides and adapted to engage the socket and the head of the tie-bar, and further provided with notched flanges, a bolt provided with a head adapted to engage said notched flanges and pass through said socket into the pot-sleeper, and bolt fastening means. 125
13. In combination a pot-sleeper having inner and outer walls and a central opening, a tie-bar provided with a head; a member on the side of the pot-sleeper having a socket, clamps adapted to engage the socket and also engage the head of the tie-bar and further provided with notched flanges; a bolt provided with a head adapted to engage said notched flanges and having a slot near its inner end, said bolt passing through said socket and entering the central orifice of the pot-sleeper, and bolt retaining means engaging said slot. 130
14. In combination a pot-sleeper having outer and inner walls, and a socket, a tie-bar provided with a head; clamps adapted to engage the socket and the head of the tie-bar; a bolt engaging the clamps, a sleeve surrounding said bolt between the outer and inner walls of the pot-sleeper and means to fasten the bolt. 135
15. In combination a pot-sleeper having outer and inner walls, a member on the outer wall of the pot-sleeper provided with a tapered socket; a tie-bar provided with a head; clamps adapted to co-act with the tapered walls of the socket and to engage the head of the tie-bar; a bolt engaging the clamp members; a sleeve surrounding said bolt between the outer and inner walls of the pot-sleeper; and means to fasten the bolt. 140
16. In combination a pot-sleeper having outer and inner walls, a member applied to the side of the pot-sleeper provided with a socket; a tie-bar provided with a head; clamps adapted to enter the socket and to engage the head of the tie-bar; a bolt engaging the clamp-members near its inner end and a wedge adapted to pass through a slot in said bolt and bind against the wall of the central orifice of the pot-sleeper. 145
17. In combination a pot-sleeper having outer and inner walls, a member applied to the side of the pot-sleeper provided with a socket having tapered walls; a tie-bar provided with a head; clamps adapted to co-act with the tapered walls of the socket and engage the head of the tie-bar; a bolt engaging the clamp-members and provided 150

with a slot near its inner end; a sleeve surrounding said bolt between the outer and inner walls of the pot-sleeper and a wedge adapted to pass through the slot in said bolt 5 and bind against the inner wall of the pot-sleeper.

18. In a railroad tie, the combination of opposite pot-sleepers, each provided with outer and inner walls; a tie-bar; a member 10 on the side of each sleeper having a socket, clamps adapted to engage the socket and an end of the tie-bar, and provided with base flanges; a bolt head adapted to engage with said base flanges and adapted 15 to extend through said socket and walls of the adjacent pot-sleeper, and means for fastening said bolt.

19. In a railroad tie, the combination of opposite pot-sleepers, each provided with a 20 central orifice, and outer and inner walls; a tie-bar; a member on the side of each sleeper having a socket; clamps to engage the socket and an end of the tie-bar, and provided with base flanges; a bolt having 25 a head adapted to engage with said base flanges and extend through said socket and said walls into the central orifice of the related pot-sleeper, and means for fastening said bolt.

30 20. In a railroad tie, the combination of opposite pot-sleepers each provided with outer and inner walls; a tie-bar provided with T-heads; a member on the side of each sleeper having a socket; clamps having 35 tapered sides adapted to engage the socket and also to engage the adjacent head of the tie-bar and provided with base flanges; a bolt having a head adapted to engage said base flanges and extending through said 40 socket and walls of the adjacent pot-sleeper, and a wedge adapted to pass through a slot

in said bolt and bind against the inner wall of the sleeper to secure said bolt.

21. In a railroad tie, the combination of opposite pot-sleepers each provided with a 45 central orifice and outer and inner walls; a tie bar provided with heads; a member applied to the side of each sleeper having a socket; clamps having tapered sides adapted to engage the socket and also to engage the 50 adjacent head of the tie-bar; a bolt provided with a slot near its inner end and a head adapted to engage said clamps and extending through said socket and said walls into the central orifice of the adjacent pot-sleeper; a sleeve surrounding said bolt between the outer and inner walls of the pot-sleeper and a wedge adapted to pass through 55 a slot in said bolt and bind against the wall of the central orifice of the pot sleeper, substantially as described.

22. A hollow pot-sleeper comprising an oval-shaped metal jacket having outwardly sloping walls and a concrete filling and provided at each end with a depending anchoring lip.

23. A hollow metal pot-sleeper comprising a top having a central orifice, an outer wall surrounding and depending from the top and an inner wall depending from the 70 top and surrounding the orifice.

24. A hollow integral metal pot-sleeper comprising a top having a central orifice, an outer wall surrounding and depending from the top, an inner wall depending from 75 the top and surrounding the orifice, and depending anchoring lips at each end of the sleeper.

In testimony that I claim the foregoing as my own, I affix my signature.

JOSEPH A. SILVER.
